UNITED STATES PATENT OFFICE.

WELLINGTON B. HOPKINS, OF DENVER, COLORADO, ASSIGNOR, BY DIRECT AND MESNE ASSIGNMENTS, TO THE SCHOOLFIELD SAFETY APPLIANCE COMPANY, A CORPORATION OF ARIZONA.

SAFETY DEVICE FOR PASSENGER-CARRYING CONVEYANCES PROPELLED BY ELECTRICITY.

1,025,091.

Specification of Letters Patent.

Patented Apr. 30, 1912.

Application filed October 4, 1909. Serial No. 520,995.

To all whom it may concern:

Be it known that I, WELLINGTON B. HOPKINS, a citizen of Canada, residing in the city and county of Denver and State of Colorado, (whose post-office address is Hotel Lafayette, in said city, county, and State,) have invented a new and useful Safety Device for Passenger-Carrying Conveyances Propelled by Electricity, of which the following is a specification, reference being had to the accompanying two sheets of drawings, which are hereby made a part hereof.

My invention relates to passenger-carrying conveyances which are either directly operated and propelled by electricity, or are made up in a train with a conveyance so propelled and operated.

My device consists in providing a means to prevent the starting of a conveyance of the class above described, while passengers are entering or alighting therefrom, the said device being of the class which wholly diverts the electric current employed to propel the conveyance, and makes it impossible for the person operating the said conveyance to turn such operating current into the motor of the conveyance, the principle involved being that of the diversion of the operating current from the motor into another circuit, or in other words to put the current propelling the conveyance temporarily out of the control of the person operating the conveyance, which objects are attained by diverting the current into another circuit.

The principal objects of my invention are:—to provide a means for preventing the sudden starting of a passenger carrying-conveyance while passengers are entering or retiring and are yet on the steps thereof, a situation shown to be productive of many accidents to passengers; to provide a means whereby the conductor, or person in charge of the conveyance, can prevent the motorman, or person operating the conveyance from starting it, if such starting would involve any danger of which the person who is operating the conveyance, from his forward position, is unaware; and generally, to obviate all negligence in the starting of such described conveyances.

Of the several views shown in the drawings, Figure 1 shows an electrically propelled car and indicates generally, the different parts involved in my device. Fig. 2 is a longitudinal section of one of the two magnet boxes employed in the operation of my device. Fig. 3 is a longitudinal section of the other magnet box required. Fig. 4 is a view in perspective of the parts shown in the magnet box in the sectional view in Fig. 2, and Fig. 5 is a similar perspective of the parts in Fig. 3. Fig. 6 is a sectional view of a controller box of an ordinary electrically propelled conveyance, showing certain of the parts of my device, and their relation to the parts in ordinary use in controlling the current propelling such conveyance. Fig. 7 is a detail in perspective of the circuit maker of my device. Fig. 8 is a cross-sectional view of a set of car steps as modified to become a part in the operation of my device. Fig. 9 is a general view of the course of the current propelling the conveyance when the said conveyance is in motion, and when my device is not in operation. Fig. 10 shows the course of the current when my device is in full operation, and shows how it is impossible for the person operating the conveyance to again start the motor, and so start the conveyance, until my device has ceased to operate.

Like characters indicate the same or similar parts in all the views shown.

The current operating the conveyance and the course it takes when the conveyance is in motion is everywhere indicated by the letter *l*, while the auxiliary or secondary course which the current is induced to follow by the operation of my device is variously indicated by the characters *n*, *n'*, *n''*, *n'''*.

T represents the ordinary trolley-pole of an electrically propelled conveyance, and *W* the overhead wire supplying the current.

h represents the motor of such conveyance, *i*, its wheels, and *j*, *j'* the points where the currents *l*, or *n*, pass into the axle and thence to the ground.

In the different views shown, *A* represents one magnet-box of my device, and *B* the other.

C. represents the step or steps of the conveyance, and D. the means by which they are adjusted to move in such a manner as to become a part in my device, such means being here displayed in the form of two upright posts fixed solidly in the general body of the car and at each end of the set of steps, which said posts pass through holes properly placed in the steps themselves and of such size as to permit the steps to move slightly upon them.

E. and E' represent two metal contacts placed in magnet-box A, and in connection with the circuit which the electric current follows when it is propelling the conveyance. E'. and E' represent another pair of metal contacts placed in the magnet-box B, and in connection with the circuit which the current takes when the conveyance is not in motion and when my device is in operation. F. and F. and J. and J. are two pairs of electro-magnets, arranged respectively in the same two magnet-boxes, and in connection with the course which the current takes when my device is in operation, that is, when the conveyance is not in motion and cannot be put in motion.

G. H. and K. L. represent the parts entering into the composition of two bars designed to be arranged in the magnet-boxes A. and B. and in relation to the electro-magnets therein contained as indicated. Of these bars, the parts H. and L. respectively, are preferably of wood, while G. and K. respectively are of iron. In operative connection with these bars as indicated, are springs I. and I. and M. and M. respectively, which are attached one end to the wooden portion of the bars aforesaid and the other to some proper and convenient part of the box itself. The office of these several springs is to hold the said bars to which they are attached in position, respectively, one against the metal contacts in magnet-box A. as indicated in Fig. 9, and the other away from the metal contacts E'. and E'. in magnet-box B. as indicated in Fig. 3. They should of course, be of such strength that, while they will hold the said bars in the positions indicated when no other force is acting, yet they will not prevent the bars being drawn away from the positions indicated in the figures designated by the action of the electromagnets, whenever the same are rendered active.

O. represents a projection of the ordinary controller lever N. of an electrically propelled conveyance, in direction diametrically opposed to the general direction of the lever itself from the shaft to which the lever is attached.

P. represents the ordinary controller box as regularly installed in conveyances of the class mentioned. Q. represents a small box

or casing conveniently placed and attached inside the said controller box, so as to permit certain special parts which are placed therein to come into operative adjustment with the projection O. of the controller lever, above described. Of these said special parts, the part U. is designed to pass upward through a slot properly placed in the top of the controller box, and in its upward position to engage the said projection O. of the controller lever, when the said lever is turned in the direction which it ordinarily takes in assuming the "off" position, the position when the current is turned off from the motor. This part U. is preferably of the form shown in Figs. 6 and 7, and is preferably of steel, modified at the end toward U'. into a flat spring, at which point attachment is made of it to the base of the box Q. This construction permits the part to be forced down by pressure, and causes it to resume its former position when pressure is removed. The pressure ordinarily is applied in the operation of the device by the projection O. engaging the curve of U. at a point below its greatest height, and as the lever is turned further, O. moves up the curve, and U. is depressed as described. To the lower part of the forward end of U. is affixed the wooden block t. to the lower surface of which is attached the metal contact piece v.

v'. and v'. are two metal contacts fixed upon the upper surface of a wooden base attached to the bottom of the box Q., as indicated, under which said base is preferably placed a flat bent spring Z. to insure the proper position of v'. v', and to permit of some little flexibility of adjustment. The contacts v'. and v'. should be slightly separated from each other as indicated.

R. indicates another small box, also preferably placed in the interior of the controller box P. This box contains two metal contacts y. and y'. y' being fastened at the end of a flat spring as indicated.

z. represents a pin-plunger whose lower end is normally in adjustment on the flat spring mentioned. On the lower part of the spring piece may be attached a pin g. which if depressed will be brought down upon an ordinary push button operating a bell attachment, and causing the bell to ring. The parts in this last described box constitute a means which in emergency would permit the person in charge of the operation of the conveyance to break the circuit which the operating current takes when my device is in use, and to divert it again into the motor of the conveyance, and so start it.

b. and c. in Fig. 8 are two metal contacts, one being attached at some convenient point to one of the steps of the conveyance, and the

other to a part of the frame of the conveyance itself.

C. C. represent the one or more steps for ingress or egress from the conveyance. 5 These steps are modified and designed so as to be slightly movable or compressible. They are fitted to posts D. placed upright and designed to pass through proper holes in the steps themselves, as before described.

10 f. represents the floor of the car which is of the ordinary form and not modified in any way necessarily.

a. represents a stout spring designed to pull up the steps and hold them in normal 15 position.

e. represents the end frame work of the steps, between which the steps are arranged and adjusted for the slight movement demanded. In normal position, then, the 20 spring a. pulls up the steps, and draws contact b. away from contact c., but when the steps are moved downward, as by a person stepping upon one or more of them, the contacts b. and c. are brought together, as 25 indicated in Fig. 10. It is immaterial upon which of the steps pressure is applied as they should be constructed in one rigid series, and movement of any one induces corresponding movement in all.

30 d. d. represent heaters properly placed under the several steps. They may well be of the ordinary type used in heating the conveyance, and for that purpose placed under the seats. They may be supplied with a current 35 from the same source. They are designed to facilitate the movement of the steps that they may play their part in the operation of my device, in that they keep the said steps free from accumulations of ice and snow. They 40 would further be of value to the operating company in preventing passengers from slipping from the steps in severe weather, as is now frequently the case.

The operation of my device is indicated 45 as follows. When the conveyance is in motion, and the controller in proper position therefor, the current propelling the conveyance passes from the trolley-pole and follows the course indicated in Fig. 9 to the controller box, to the motor and thence to the ground, completing the operating circuit. But when the conveyance is stopped and the controller consequently moved to the "off" position to cut off the current, the part U. 50 is depressed by the action of O. as before described, and bar v. is brought into contact with the parts v'. and v'' completing a circuit at that point, and if at the same time, any passenger be upon the steps C. C. they 55 are depressed and contacts b. and c. brought together as described, completing a circuit at that point. Thus then, a secondary circuit, as indicated in Fig. 10, is immediately established, from the point where the wire n.

is attached to wire l. as shown in Fig. 2, 65 around the electro-magnets F. and F. passing between them through wire n'. thence around electro-magnet J. thence to contact piece E'. passing between them through wire n''. thence to contact v'. passing 70 through wire n. to contact bar v. to contact v'. to contact E'. passing through wire n. to electro-magnet J. passing between them through wire n'''. thence to contact b. on steps, to contact c. thence to the axle at j'. 75 and thence to the ground. And so soon as this circuit is thus established, the electro-magnets F. and F. become active and draw down the bar G. H., thus making a break in the main circuit at this point, the 80 main circuit being the circuit operating the conveyance. Also, the electro-magnets J. and J. become active and draw up the bar K. L. in box B. as shown in Fig. 10, and a circuit is established directly between the 85 contacts E'. and E'. without reference to the parts v. and v'. and v''. so that though the controller lever be turned back to the "on" position in an endeavor to start the conveyance, and the part U. being thereby 90 released, fly upward and separate the points of contact before made by it as described, yet as the circuit has now been directly established, as just explained, between E'. and E'. the current cannot be thereby 95 turned into the motor, and the conveyance started, for not only has the current a complete circuit to follow as indicated, but also the direct, or operative circuit, is still broken in magnet-box A. between E. and E., as before described. And this will continue as long as there is any pressure upon the steps, in other words primarily, as long as any passengers are getting on or off, or as long as the person in charge of the conveyance is 100 maintaining a pressure on the steps, as he might do by stepping on them himself in case of a danger of which the person operating the conveyance was unaware. But if the pressure be removed from the steps C. C. 110 then the spring a. draws them up to normal position again, and the secondary circuit is immediately broken at that point, by the separation of the contacts b. and c. Immediately, then, the electro-magnets F. and F. and J. and J. cease to be active, and cease to attract the bars G. H. and K. L. Bar G. H. is then drawn up again by the springs I. and I. into contact with E. and E. and the operative circuit is restored at that point 115 120 as before. Also bar K. L. is drawn down by the springs M. and M. Whereupon, if the controller lever be in the "on" position, the conveyance may be operated as before.

Inasmuch as it might be deemed of importance in times of emergency to have a means of breaking the secondary circuit and restoring the current to the control of the 125

person operating the conveyance, though pressure is still present upon the steps of the conveyance, the device shown in box R. and above described may be installed. In ordinary conditions the contacts y , and y' would always be in engagement, and the n. current or secondary current upon which they are in connection would consequently pass through them unobstructed in the general working of my device as above fully described. But if the pin-plunger x be depressed then the contacts y , and y' are forced apart by the downward movement of the plunger and the consequent yielding of the steel spring support upon which y' is mounted, and the secondary circuit is thereby broken at that point with all the attendant results as explained in connection with its breaking by removal of pressure from the steps. It is entirely optional with the parties operating the conveyances whether or not this emergency device be installed, and if it is installed and is ever used the ringing of the bell which forms a part of the emergency device as above described, will at once notify all present that this extraordinary way has been employed to start the car.

The particular form of the different parts as herein shown and described is not to be deemed material, and I do not limit myself to them. Neither is the specific location in the conveyance itself of the different parts involved of any consequence. All that is essential to the operation of the device as described is that the relative position of the several parts to each other in the circuit be preserved.

Changes within the scope of the invention may be made without altering the principle involved.

My claims are:—

1. In a safety device, a car, a movable step, a circuit-closer operated by said step, car propelling means, a control circuit including said circuit-closer for rendering said car propelling means ineffective, and means for interrupting said control circuit when the car is moving, substantially as described.

2. In a safety device, a car, a movable step, car propelling means, a control circuit for said car propelling means, means in said control circuit operated by said step for rendering said car propelling means inoperative, and means for rendering said control circuit ineffective when the car is in motion, substantially as described.

3. In a safety device, a car, a movable member on said car, a motor, a motor circuit, a control circuit for said motor circuit, and means in said control circuit operated by said movable member for shunting the current from said motor circuit into said control circuit.

4. In a safety device, a car, a movable

step, a motor circuit, a secondary circuit, 65 and means to divert current from said motor circuit into said secondary circuit and retain it there when pressure is present upon said step, substantially as described.

5. In a safety device, a car, a movable 70 member on said car, a motor circuit, a control circuit independent of the motor circuit, and means to divert current from the motor circuit into said control circuit and retain it there when said movable member is 75 forced from its normal position, substantially as described.

6. In a safety device, a car, a motor, a 80 motor circuit, a movable member on said car, a circuit-closer operated by said movable member, a control circuit and including said circuit-closer, an electro-magnetic circuit-breaker for the motor circuit having its windings in said control circuit, means for shunting the current from said motor circuit into said control circuit, and means for preventing the operation of said current shunting means when the car is in motion, substantially as described.

7. In a safety device, a car, a movable 90 member on said car, a motor circuit, a control circuit, means in said control circuit for opening and closing said motor circuit, and means for diverting current from the motor circuit into said control circuit when said movable member is forced from its normal position, substantially as described.

8. In a safety device, a car, a motor, a 100 motor circuit, a movable member associated with said car and fitted with a circuit-closer, a control circuit including certain electro-magnets and means for opening the motor circuit, means for closing said control circuit when the current is shut off from the motor and said circuit-closer is closed, the 105 whole comprising means for diverting the current from the motor into said control circuit, substantially as described.

9. In a safety device, a car, a motor, a 110 motor circuit, a movable member on said car, a circuit-closer operated by said movable member, a secondary circuit including said circuit-closer, a circuit-breaker for the motor circuit having its windings in said secondary circuit, a controller for the motor, an interlock operated by said controller to close said secondary circuit and open said motor circuit when said movable member is forced from its normal position and said circuit-closer is closed, substantially as described.

10. In a safety device, a car, a motor, a 120 motor circuit, a movable member on said car, means for holding said movable member in a normal position, a circuit-closer operated by said movable member, a secondary circuit including said circuit-closer, means 125 for energizing said secondary circuit to in-

terrupt said motor circuit when the car is at rest and said movable member is forced from its normal position, and means for preventing interference with said motor circuit by said movable member regardless of its position when the car is moving, substantially as described.

In testimony whereof I have hereunto

signed my name in the presence of two witnesses, at Denver, in the State of Colorado, 10 this 2nd day of September, 1909.

WELLINGTON B. HOPKINS.
